MEANS FOR CONTROLLING BIT ACTION

William H. Clapp, Pasadena, Calif.

Application January 27, 1945, Serial No. 574,835

5 Claims. (Cl. 255—19)

1

This invention relates to the art of rotary drilling with special reference to the art of drilling wells. The invention is directed specifically to a highly novel means for accelerating the rate of drilling by continuously controlling the action of the drilling bit by compounding percussive motion with rotary motion whenever desirable.

Many attempts have been made to cause a rotating bit to drill with percussion. The advantages of percussive drilling, particularly in hard strata, have long been appreciated, as evidenced by the continued use of "cable tool" methods. Such advantages can occasionally be secured with rotary drilling equipment if successive beds of hard and soft strata are encountered by the bit, since the jet of drilling mud ejecting from the rotating bit may wash through a layer of sand or unconsolidated material and allow the drill to fall upon the underlying rock and bounce rhythmically during the oscillatory elongations of the elastic drill pipe.

Occasionally such percussive action can be initiated by causing the rotating bit to stick momentarily, if the drill pipe is lowered too rapidly; during this moment of inaction the rotating drill pipe continues to "wind up," twisting into a spiraled form which tends to shorten the drill stem and decrease the pressure of the bit upon the bit-stratum, thus tending to free the stalled bit and thus release the torsional energy stored in the stressed drill pipe. The subsequent percussion of the bit is actuated by the oscillatory elongations of the elastic drill stem. The value of these artificial methods of inducing oscillation is limited, of course, since drilling conditions are seldom favorable. For example, the effectiveness of percussion would be greatest during the drilling of a tough limestone "shell," hard shale or other relatively impervious or impenetrable strata but in these cases oscillation can hardly be induced.

The imperative necessity of employing percussion for such hard rock drilling may be emphasized by directing attention to the well known fact that such difficulties frequently encourage the crude practice of actually elevating the bit ten or twenty feet "off bottom," then dropping the entire rapidly rotating "drill-string" and attempting to interrupt this descent by means of the hand brake operated by the driller, who thus attempts to restrain the falling drill pipe before damage is incurred. Repetition of this crude and arduous procedure increases the obviously inherent risk of bending the drill pipe and over-stressing the threaded connections in the couplings. On account of such dangerous practices, many at-

2

tempts have been made to transform the rotary motion of the bit into a percussive motion.

The various devices advocated for this purpose have failed to receive approval or general acceptance in the art either as a result of the impracticability of their design or because the intensity of the percussion thus imparted to a bit was relatively negligible. Such prior devices have been particularly unsatisfactory because their construction merely provided continuous weak percussion without incorporating any means for preventing percussion or controlling the intensity thereof or increasing the available bit torque.

Intense percussion is a primary objective of this invention.

It has been discovered that terrific impact may be delivered by a rotary bit by employing an automatic means for completely disengaging the bit and lifting both the bit and the drill collar before allowing the falling drill collar to drive the rotating bit into the bit-stratum.

A primary objective of this invention is to secure maximum percussive effect by utilizing the expansion of the compressed drill pipe and the momentum of the falling drill collar to drive the bit.

Another paramount purpose of the invention is to provide a means for controlling bit percussion, such control being operated by the driller.

This feature of the invention guarantees positive regulation of the intensity of percussion and therefore includes the opportunity of employing discretion, as well as percussive power, since such action may be utilized whenever highly consolidated or tough strata are encountered; alternatively, such action may be entirely eliminated in favor of high torque rotation whenever the driller so elects, as when soft or unconsolidated strata are penetrated.

A major objective of the invention is to provide an automatic means for not only generating percussion but also for combining intense percussive action with high torque rotary action and delivering such compound action to the bit, whenever the driller so desires.

A further purpose of the invention is to provide for the regulation of the automatic means for generating percussion by merely varying the bit pressure, as indicated by the "weight indicator" and controlled by the driller.

Another objective of the invention is to prevent "twist offs" of the drill stem by providing an automatic means for generating percussion whenever the torsional stress in the drill pipe

reaches a predetermined maximum allowable working load.

Another advantage sought by this invention is that of automatically regulating the bit torque by controlling the bit pressure.

By means of this invention I also propose to conserve the drilling time which is conventionally dissipated whenever a "round trip" is required in order to replace a "drag bit" or "fish-tail" bit with a "rock bit" or roller-cutter bit.

The achievement of the aforesaid objectives by creating a means whose structural rigidity and indestructibility and simplicity affords adequate protection against failure, defines a principal purpose of the invention.

The structural principles which indicate the efficiency of the proposed means of controlling bit action also indicate that such efficiency is substantially independent of the form and arrangement of certain auxiliary features. Therefore, although the following disclosure of the invention is illustrated by a specific embodiment, it should be clearly understood that such reference is merely intended as illustrative.

Referring to the drawings, Fig. 1 is an elevational view of the "drilling tools" employed in conventional rotary drilling practice, including the bit, the drill pipe, the derrick floor, the rotary table, the "kelly," the swivel, the flexible "mud hose" connected to the slush pump and the "traveling block" supported by the "drilling line" or cable; the associated "crown block" and derrick structure are not shown.

Fig. 2 exemplifies a vertical section of the upper portion of the proposed means for controlling bit action.

Fig. 3 illustrates a longitudinal view, partly in section, of the lower portion of the proposed controlling means.

Fig. 4 shows a plan view of a transverse section taken along the line A—A of Fig. 3.

Figs. 5 and 6 delineate an alternative embodiment of the invention, Fig. 5 representing the upper portion and Fig. 6 representing the lower portion thereof.

Fig. 7 reveals a plan view of a transverse section taken along the line B—B of Fig. 5.

Figs. 8a, 8b, 8c and 8d represent schematic diagrams showing mutual displacement of cam-shaped projections, produced by relative rotation of a pair of cam rings.

Referring in detail to Fig. 1, the so-called "drilling tools" 10 of a rotary drilling system 20 are delineated diagrammatically. The bit-stratum 11 is drilled by the action of a rotatable or percussive bit 12 which is conventionally rotated by a drill collar 13. However, the position of the proposed means 30 for controlling bit action is exemplified as intermediate between the bit 12 and the drill collar 13. The latter is attached to, and actuated by, drill pipe 14, portions of which are shown within walls 15 and casing 16 which define the drill hole. The drill pipe 14 passes through a derrick floor 17 and rotary table 18 and engages a "kelly" 19 which is supported by a swivel 21, swivel bail 22, hook 23, traveling block 24 and drilling line or cable 25. The conventional rotary drilling system 20 also includes a continuous circulation of drilling mud which is delivered to the interior of the drill stem 14 by flexible hose 26 and "stand pipe" 27 which connect a "slush pump" 28 to the swivel 21, such drilling mud being ejected from the bit and then returned to the surface through the annular space

between the drill pipe 14 and the walls 15 of the drill hole.

Fig. 2 illustrates the upper portion of the means 30 for controlling the action of the bit 12. A tubular driving member 31 is attached to the lower end of the drill collar 13, or connected thereto by means of an intermediate coupling member or sub 32 threaded for this purpose. The driving member 31 actuates a driven member 51 which is threadedly connected to the bit 12 or to an intermediate coupling member or sub 52 which may be seen in Fig. 3. This driving member 31 actuates several associated elements which will be collectively designated as the driving assembly 40 since these components could be consolidated into a single driving unit, although many advantages of the preferred construction would be sacrificed thereby.

The driving member 31 is exemplified in Figs. 2 and 3 as a very strong steel sleeve formed with a relatively thicker wall in the central portion 31—b than in the upper and lower portions 31—a and 31—c, respectively, in order to provide inwardly extending shoulders 33 and 34 therebetween. The lower end of the sleeve 31 is externally threaded for connection with an abutment member or special coupling 35 whose lower surface 36 is serrated or notched, preferably with square teeth, in order to engage a complementary surface 37 formed on the upper surface of a hardened steel ring or displacement member 38 whose lower surface is characterized by two or more equally spaced cam-shaped projections 39 having flat ends or dwell surfaces 39—a and inclined sides 39—b such projections being separated by engagement surfaces 39—c.

This cam ring 38 is adapted for releasable engagement with a corresponding element 58 which actuates several associated elements which 40 will be collectively designated as the driven assembly 50.

The displacement member 58 is similar in form to the cam ring 38, although inverted with respect thereto, having an upper surface which is characterized by two or more equally spaced cam-shaped projections 59 having flat ends or dwell surfaces 59—a and inclined sides 59—b, such projections being separated by engagement surfaces 59—c.

50. The driven member 51 is actuated by the cam ring 58, whose lower surface 57 is notched, preferably being formed with square teeth in order to engage the complementary upper surface 56 of an abutment member or special coupling 55 which is threadedly connected to a base 54 and also supported by a shoulder 53 of the driven member 51.

50. The inner elements of the means 30 for controlling bit action are contained within an annular space 41 between the driving member 31 and the driven member 51. The latter has a relatively stronger base section 54 below a shoulder 63 where the diameter decreases to provide a larger annular space and an outer surface 64 within a packing ring nut 42 which is threadedly connected to the inner surface of the abutment member 35.

This packing ring nut 42 compresses a packing spring 43, a retaining ring 44 and packing material 45 which seals the lower end of the annular space 41 against the entrance of drilling mud. The packing material 45 is restrained by a packing ring 47 which is immobilized by the lower surface of the inwardly extending shoulder 34 75 provided by the driving member 31.

The compression of a coiled spring or resilient means 60 provides a force which compresses the displacement means 38 and 58 by urging the driving assembly downwardly and driven assembly upwardly. This effect is secured by compressing the coiled spring 60 between a lower restraining ring 48 and an upper restraining ring 65, the former being supporting by the shoulder 33 and the latter being restrained by an anti-friction bearing 66 which bears against an adjusting means or sleeve nut 67. This bearing 66 minimizes the torsional deformation of the coiled spring 60 during percussion.

A packing member 49 seals the upper end of the annular space 41 against the entrance of drilling mud. The upper end of the packing member 49 is externally threaded for connection with the driving member 31-a. An inwardly extending shoulder 49-a supports packing material 49-b which is compressed by a packing spring 49-c restrained by an externally threaded packing nut 49-d. The latter is axially bored to provide a tubular surface 49-e.

During relative rotation of the driving assembly 40 with respect to the driven assembly 50, mutual alignment of the driving member 31 and the driven member 51 is maintained by close fitting bearing surfaces 64 and 68, the latter being adjacent to the aforesaid tubular surface 49-e.

Fig. 4 indicates a plan view of a transverse section taken along the line A-A of Fig. 3 showing the lower cam ring 58 which in this case is characterized by four cam-shaped projections spaced at equal angular intervals. The cylindrical bore 69 of the driven member 51 conducts the drilling mud therethrough.

Figs. 5, 6 and 7 exemplify an alternative embodiment of the invention. The reference characters in these illustrations will be distinguished by primes from those previously employed, in order to indicate the correspondence between analogous elements of the control means 30 and 30'.

A tubular driving member 31' is attached to the lower end of the drill collar 13 or connected thereto by means of an intermediate coupling member or sub 32' threaded for this purpose. The driving member 31' actuates a driven member 51' which is threaded to the bit 12 or to an intermediate coupling member or sub 52'. This driving member 31' actuates several associated elements which will be collectively designated as the driving assembly or driving unit 40' since these elements could be consolidated into a single driving member, although many advantages of the preferred construction would be sacrificed thereby.

The driving member 31' is exemplified in Figs. 5 and 6 as a very strong steel sleeve formed with a relatively thicker wall in the lower portion 31'-b than in the upper portion 31'-a, in order to provide an inwardly extending shoulder 33' therebetween. The lower end of the sleeve 31' is internally threaded for connection with an abutment member or special coupling 35' whose lower surface 36' is serrated or notched, preferably with square teeth in order to engage a complementary surface 37' formed on the upper surface of a hardened steel ring or displacement member 38' whose lower surface is characterized by two or more equally spaced cam-shaped projections 39' having flat ends or dwell surfaces 39'-a and inclined sides 39'-b, such projections being separated by engagement surfaces 39'-c.

This cam ring 38' is adapted for releasable

engagement with a corresponding element 58' which actuates several associated elements which will be collectively designated as the driven assembly or driven unit 50'.

The displacement member 58' is similar in form to the cam ring 38', although inverted with respect thereto, having an upper surface which is characterized by two or more equally spaced cam-shaped projections 59' having flat ends or dwell surfaces 59'-a and inclined sides 59'-b, such projections being separated by engagement surfaces 59'-c. The driven member 51' is actuated by the cam ring 58', whose lower surface 57' is notched, preferably being formed with square teeth in order to engage the complementary upper surface 56' of an abutment member or special coupling 55' which is threadededly connected to the base 54' and also supported by the shoulder 53' of the driven member 51'.

The inner elements of the controlling means 30' are contained within the annular space 41' between the driving member 31' and the driven member 51'. The latter has a relatively stronger base section 54' below a shoulder 63' above which the diameter decreases to provide a larger annular space and an outer surface 64' within a restraining ring 42' which is supported by the upper surface of an inwardly extending shoulder 34' of the driving member 31'.

The compression of a coiled spring or resilient means 60' provides a force which compresses the displacement means 38' and 58' by urging the driving assembly downwardly and the driven assembly upwardly. This effect is secured by compressing the coiled spring 60' between the lower restraining ring 42' and an upper restraining ring 65', the former being supported by the shoulder 34' and the latter being restrained by an anti-friction ring 66' which bears against an adjusting means or sleeve nut 67'. This frictional drag of the thrust bearing ring 66' increases the torsional moment applied to the driven unit 50'.

The compression of a second coiled spring or resilient means 70 provides an additional force which further compresses the displacement means 38' and 58' by urging the driving assembly downwardly and the driven assembly upwardly. This effect is secured by compressing the coiled spring 70 between a lower restraining ring 71 and an upper ring 72, the former being supported by the shoulder 33' and the latter being restrained by an anti-friction ring 73 which bears against an adjusting means or sleeve nut 74. This anti-friction ring 73 minimizes the torsional deformation of the coiled spring 70 during percussion.

A packing member 49' seals the upper end of the annular space 41' against the entrance of the drilling mud. The upper end of the packing member 49' is externally threaded for connection with the driving member 31'-a. An inwardly extending shoulder 49'-a supports packing material 49'-b which is compressed by a packing spring 49'-c restrained by a packing nut 49'-d. The latter is axially bored to provide a tubular surface 49'-e.

During relative rotation of the driving unit 40' with respect to the driven unit 50', mutual alignment of the driving member 31' and the driven member 51' is maintained by close fitting bearing surfaces 64' and 68', the latter being adjacent to the aforesaid tubular surface 49'-e.

Fig. 7 indicates a plan view of a transverse section, taken along the line B-B of Fig. 5 showing the adjusting means or sleeve nut 74 threadedely

connected to the tubular driven member 51' and surrounded by the driving member 31'-a. The cylindrical bore 69' of the driven member 51' conducts the drilling mud therethrough.

The means 30 for controlling bit action may be employed for generating percussion, for controlling the intensity thereof and for controlling the maximum torque transmitted to the bit.

The maximum torque or disengagement torque which may be applied to the driven unit 50 by the driving unit 40 may be defined as the limiting value of torsional moment which may be sustained by the engagement of the cam rings 38 and 58 without causing them to disengage. Whenever this disengagement torque is exceeded by the driving torque, the upper cam ring 38 will be rotated upon, and with respect to, the lower cam ring 58.

This rotation will be impeded, of course, by the intermittent re-engagement of the projections 39 and 59, such periodical re-engagement being caused by the compression of the cam rings between the driving unit 40 and the driven unit 50. This compression is equal to the force supplied by the compressed spring 60 and the reactionary force exerted by the bit-stratum in responsive opposition to the bit pressure diminished by the weight of the bit 12, the bit-sub 52, and the driven member 51. Consequently, the aforesaid disengagement torque is a variable quantity which may be increased by increasing the bit pressure and by increasing the spring compression. Hence, whenever the driving torque exceeds the disengagement torque transmitted to the driven unit, the upper cam will be rotated upon the lower cam and thus periodically displaced therefrom as the projections 39 encounter and slide over the projections 59, i. e., the bit will percuss. Therefore, the bit torque is equal to the disengagement torque as long as the bit percusses.

In order to provide a complete disclosure of the principles involved in the invention, a detailed consideration of the successive phases of a single percussion cycle is desirable.

The first phase of the percussion cycle begins when the cam rings 38 and 58 occupy the relative positions illustrated in Fig. 8a. During this first phase, the inclined surfaces 39-b slide upwardly along the inclined surfaces 59-b, thus displacing the cam rings to the position shown in Fig. 8b. The interval of time elapsing during this displacement may be designated as the "displacement time."

During this primary interval, the mutual displacement of the concentric cam rings 38 and 58 increases the bit pressure and thus increases the reactionary torque exerted by the bit-stratum in responsive opposition to the increased torsional moment of the bit. Such vertical displacement of the concentric cam rings also raises the driving member 31, elevates the drill-collar 13 and increases the compressional and torsional energy accumulated in the twisted drill-stem.

The secondary phase of the percussion cycle defines an interval of "traverse time" which elapses while the dwell surfaces 39-a slide along the dwell surfaces 59-a, a substantial wearing surface being provided therefor.

The interval of time elapsing during these primary and secondary phases of the percussion cycle is substantially greater than the subsequent interval of "closure time," a third interval which elapses while the vertically displaced cams become re-engaged, i. e., while projections 59 move vertically toward the engagement surfaces 39-c

between projections 39. At the instant of cam release the bottom of the spring 60 starts to move downwardly since it is anchored to the falling driving member 31. At the same instant the restraint on the spring 60 imposed by the cams is removed and the spring expands abruptly, thus jerking the bit off bottom before bringing the cams into their original closure.

During the fourth phase of the percussion cycle, the projections 39 rotate toward the projections 59, without causing any relative vertical displacement of the cam rings.

This is the interval of "impact time." The drill collar has been displaced upwardly, energy of compression and torsion has been accumulated in the drill pipe, the bit has been jerked off bottom with an upward acceleration several times greater than the downward acceleration of the ponderous drill collar, a prerequisite which is fulfilled by employing sufficient strength, stiffness or incompressibility in springs 60' and 70 to provide an upward force several times greater than the combined weight of the driven unit, bit and bit sub. This important prerequisite guarantees a greater upward acceleration of the driven unit than the simultaneous downward acceleration of the falling drill collar.

This is the situation at the beginning of the interval of "impact time." The cam rings are compressed. The bit is rotating more slowly than the drill collar because projections 39 are rotating toward projections 59. Angular acceleration is being imparted to the bit. Vertical acceleration is being imparted to the bit. Nothing impedes the descending bit. Therefore, the compressed drill pipe and the heavy descending mass of the drill collar drive the rotating bit into the bit-stratum with a percussion blow which is intense.

This intense impact must occur before the end of the fourth phase of the percussion cycle, i. e., before the cam rings reach the position shown in Fig. 8a, since the horizontal portions of the cam rings must be in contact at the instant of impact. For this important reason, only four cam projections 39 and 59 are illustrated in the drawings. Fewer projections assure the fulfillment of this requirement, since the duration of the fourth phase of the percussion cycle is increased thereby.

The foregoing sequence of events is repeated every time the projections 39 traverse the projections 59. Continuous percussion with high torque is thus achieved. The intensity of this available bit torque will be determined by and will increase with, the angle of inclination of the sloping sides 39-b and 59-b of the projections 39 and 59, by the compression of the cams and therefore by the bit pressure. The latter is controlled by the driller and measured by the "weight indicator."

The bit pressure is not limited, therefore, except to such values as have previously been considered low enough to assure a substantially straight drill hole and low enough to prevent "twisting off" the drill pipe. Hence the maximum bit torque, available during percussive drilling has not been decreased by incorporating the control means 30 into the drilling tools 10, since the maximum bit torque is equal to the maximum disengagement torque as determined by the maximum permissible bit pressure.

Bit percussion will be prevented by decreasing the bit pressure and thus decreasing the bit torque. Since the latter was equal to the disengagement torque during percussion and since it has now been decreased, the bit torque must

have become smaller than the disengagement torque; therefore, the bit will not percuss.

The available bit torque during non-percussive drilling may be increased with the bit pressure until it becomes equal to the disengagement torque. The available bit torque may then be further increased with the bit pressure, during percussive drilling, while the disengagement torque increases and causes the torsional stress to approach the maximum allowable torsional stress of the drill pipe. Consequently, the drill pipe can be protected against excess torsional stress by designing the control means 30 with a maximum disengagement torque which is less than the maximum allowable torsional stress of the drill pipe. This design requirement indicates an upper limit for the combined strength of the springs 60' and 70 for the slope of the sides 39—b and 59—b of the cam ring projections and for the radius of the cam rings. Hence, the use of both of the springs 60' and 70 is more important if the control means 30 is to be used with small drill pipe.

The available bit torque, during non-percussive drilling or percussive drilling may be increased, therefore, by increasing the compression of the spring 60 or by employing an additional spring 70, as exemplified in Figs. 5 and 6, or by increasing the angle of inclination of the sides 39—b and 59—b of the cam projections, or by increasing the radius of the cam rings, or by increasing the bit pressure.

The character of the bit-stratum will also determine the bit torque, since sticky or unconsolidated formations will tend to prevent the rotation of the bit and therefore tend to increase the bit torque. This drilling condition has been characterized, heretofore, by the maximum danger of "twisting off" the drill pipe. Such conventional risks are eliminated by my invention, because, whenever soft or sticky formations are drilled the optimum bit pressure is relatively low; hence the disengagement torque is relatively low; consequently, if the increased bit torque is excessive, it will become equal to the disengagement torque and the bit will therefore percuss, thus relieving the excess torsional stress in the drill pipe.

These considerations may be expressed more explicitly by means of the mathematical relationship between these variables.

The intensity of percussion may be increased by increasing the bit pressure, by increasing the compression of the cam rings, by increasing the compression of the spring 60, by increasing the angle of inclination of the sides 39—b and 59—b of the cam projections, or by employing an additional resilient means 70 as exemplified in Figs. 5 and 6.

A paramount feature of this invention is the mechanical design of the control means 30, whose simplicity allows structural rigidity, as exemplified by the indestructability of the few heavy moving parts. Furthermore, the design provides for continuous cooling of the cam rings by the circulating drilling mud. These meritorious considerations guarantee positive action and durable service.

The design of the control means 30 is unique. Terrific impact may be delivered by a rotating bit by employing this automatic means for completely disengaging the bit and lifting both the bit and the drill collar before allowing the falling drill collar to drive the rotating bit into the bit-stratum. The intensity of this impact may be controlled by the driller by regulating the bit pressure.

Such positive regulation of the intensity of percussion enables the driller to employ discretion, since percussive action may be utilized by increasing the bit pressure whenever tough or highly consolidated strata are encountered.

This bit pressure control allows the driller to act in accordance with conventional practice, since percussion may be eliminated in favor of high-torque rotation whenever this is considered preferable.

This invention utilizes a completely new principle in the art of drilling and discloses a method of controlling the action of the bit. Various uncontrollable contrivances have been proposed, heretofore, whereby a weak impulse was delivered to the bit and thus partially transmitted to the bit-stratum. The effectiveness of such prior methods has been destroyed by the inertia of the bit, since the impulse absorbed by the bit was not necessarily transmitted to the bit-stratum; instead, most of the impact energy was dissipated by vibrating or deforming the bit, rather than the bit-stratum.

My invention guarantees the delivery of all of the impact energy to the bit-stratum by accumulating potential energy in the bit, in the control means and in the drill collar during the elevation of these members by an ingenious automatic control means which suddenly releases all of this potential energy by allowing these members to fall upon the bit-stratum.

This fundamental principle of drilling with a falling bit and drill collar necessitates the use of sufficient spring force to accelerate the bit upwardly at a rate which exceeds the downward acceleration of the falling drill collar, since this requirement guarantees that the bit will be lifted off bottom before the percussion blow. In order to utilize this principle effectively it is preferable to design the engagement surfaces 39—c and 59—c substantially longer than the dwell surfaces 39—a and 59—a, an expedient which provides for the relative rotation of these surfaces during the "impact interval" of the percussion cycle. This consideration guarantees that these surfaces will be engaged at the instant of impact.

The various objectives of the invention have been achieved. Intense percussive action has been combined with high-torque rotation. Such compound action may be generated and controlled whenever desired. Such regulation is visibly evidenced by the "weight indicator."

Protection against twisting-off the drill stem is provided by an automatic means for generating percussion whenever the torsional stress therein reaches a predetermined maximum allowable working stress.

The preferred form of my invention described herein in specific detail for the purpose of disclosure and to illustrate the principles involved, will suggest to those skilled in the art various changes, modifications and substitutions that do not depart from my underlying concept, I reserve the right to all such changes, modifications and substitutions that properly come within the scope of my appended claims.

I claim as my invention:

1. A combination of parts for use in the rotary system of drilling wells, which comprises: a drill pipe extending from the bit assembly and upwardly through the well to a point above the top of the well bore; means above the top of the well bore for rotating the drill pipe; means for supporting all or a part of the weight of the drill

11

pipe; an upper displacement member having an upper interrupted cam on the lower end thereof; means rigidly connecting the upper displacement member to the drill pipe; a lower displacement member having a lower interrupted cam on the upper end thereof, said upper and lower cams being in contact with each other when the bit is in firm contact with the bottom of the well and being so formed that when the upper displacement member rotates at a faster rotative speed than the lower displacement member the displacement members are alternately forced apart and allowed to come together; a compression spring so placed that it exerts an upward pressure on an extension on said lower displacement member and the same pressure downwardly on said upper displacement member, said pressure being substantially greater than that needed to lift the lower displacement member and all parts carried thereby and hold the lower interrupted cam in firm contact with the upper interrupted cam while the bit is in actual use; and means rigidly connecting the lower displacement member to the bit.

2. A combination of parts for use in the rotary system of drilling wells, which comprises: a drill pipe extending from the bit assembly and upwardly through the well to a point above the top of the well bore; means above the top of the well bore for rotating the drill pipe; means for supporting all or a part of the weight of the drill pipe; an upper displacement member having an upper interrupted cam on the lower end thereof; means rigidly connecting the upper displacement member to the drill pipe; a lower displacement member having a lower interrupted cam on the upper end thereof, said upper and lower cams being in contact with each other when the bit is in firm contact with the bottom of the well, the effective coacting surfaces of said cams being of a shape that would be generated if a line radial to the axis of said assembly were rotated about and synchronously advanced upwardly along said axis; a compression spring so placed that it exerts an upward pressure on an extension on said lower displacement member and the same pressure downwardly on said upper displacement member, said pressure being substantially greater than that needed to lift the lower displacement member and all parts carried thereby and hold the lower interrupted cam in firm contact with the upper interrupted cam while the bit is in actual use; and means rigidly connecting the lower displacement member to the bit.

3. A combination of parts for use in the rotary system of drilling wells, which comprises: a drill pipe extending from the bit assembly and upwardly through the well to a point above the top of the well bore; means above the top of the well bore for rotating the drill pipe; means for supporting all or a part of the weight of the drill pipe; an upper displacement member having an upper interrupted cam on the lower end thereof; means rigidly connecting the upper displacement member to the drill pipe; a lower displacement member having a lower interrupted cam on the upper end thereof, said upper and lower cams being in contact with each other when the bit is in firm contact with the bottom of the well and being so formed that when the upper displacement member rotates at a faster rotative speed than the lower displacement member the displacement members are alternately forced apart and allowed to come together; a compres-

12

sion spring coaxial with said assembly; a tension member rigidly secured to one of said displacement members and extending through said spring; a head on said tension member against which one end of said compression spring abuts, the other end of said spring abutting against the other displacement member in such a manner as to force said displacement members toward each other with sufficient force to hold the cams thereon in close engagement with each other against the weight of any parts which might pull said cams apart when the bit is in use; and means rigidly connecting the lower displacement member to the bit.

- 10 4. A combination of parts for use in the rotary system of drilling wells, which comprises: a drill pipe extending from the bit assembly and upwardly through the well to a point above the top of the well bore; means above the top of the well bore for rotating the drill pipe; means for supporting all or a part of the weight of the drill pipe; an upper displacement member having an upper interrupted cam on the lower end thereof; means rigidly connecting the upper displacement member to the drill pipe; a lower displacement member having a lower interrupted cam on the upper end thereof, said upper and lower cams being in contact with each other when the bit is in firm contact with the bottom of the well, the effective coacting surfaces of said cams being of a shape that would be generated if a line radial to the axis of said assembly were rotated about and synchronously advanced upwardly along said axis; a compression spring coaxial with said assembly; a tension member rigidly secured to one of said displacement members and extending through said spring; a head on said tension member against which one end of said compression spring abuts, the other end of said spring abutting against the other displacement member in such a manner as to force said displacement members toward each other with sufficient force to hold the cams thereon in close engagement with each other against the weight of any parts which might pull said cams apart when the bit is in use; and means rigidly connecting the lower displacement member to the bit.
- 15 5. In a mechanism for attachment at its upper end to the lower end of a drill pipe which is rotated in a well by means old in the art, said means engaging and rotating the upper end of said drill pipe, the drill pipe rotating said mechanism, and rotating a bit attached to the lower end of said mechanism, the combination of: an upper displacement member having an interrupted cam on the lower end thereof, the drill pipe being rigidly connected to said upper displacement member which therefore turns at all times with said drill pipe, said drill pipe exerting downward pressure directly on said upper displacement member; a lower displacement member having a lower interrupted cam on the upper end thereof, the bit being rigidly connected to said lower displacement member, said cams having faces which cooperate to first force said members apart and then allow the upper displacement member to drop and strike a blow on the lower displacement member; and a compression spring so placed that the upper end of said spring exerts an upward pressure on an extension of said lower displacement member and the lower end exerts the same pressure downwardly on said upper displacement member, said pressure being substantially in excess of that needed to lift the lower displacement member and its attached

Certificate of Correction

January 24, 1950

Patent No. 2,495,364

WILLIAM H. CLAPP

It is hereby certified that errors appear in the printed specification of the above numbered patent requiring correction as follows:

Column 6, line 51, for the words "and upper" read *an upper*; column 14, line 8, list of references cited, for "Feb. 28, 1933" read *Feb. 28, 1932*; same column, under the heading "FOREIGN PATENTS" add *145,349 Germany ----- Nov. 10, 1903*;

and that the said Letters Patent should be read with these corrections therein that the same may conform to the record of the case in the Patent Office.

Signed and sealed this 30th day of May, A. D. 1950.

[SEAL]

THOMAS F. MURPHY,
Assistant Commissioner of Patents.
